TRAVELING WELDER

Anton Waeschle and Robert E. Allan, Detroit,
Mich., assignors to General Motors Corporation,
Detroit, Mich., a corporation of Delaware

Application April 25, 1938, Serial No. 204,115

20 Claims.

(Cl. 219—4)

This invention relates to a traveling spot welder which is adapted to weld "on the fly."

In the drawings:

Fig. 1 is a front elevation.

Fig. 2 is a side elevation.

Fig. 3 is a plan view.

Fig. 4 is a fragmentary front elevation partly in section.

Fig. 5 is a section on the line 5—5 of Fig. 4.

Fig. 6 is a section on the line 6—6 of Fig. 4.

Fig. 7 is a section on the line 7—7 of Fig. 5.

Fig. 8 is a front elevation of the third rail brushes.

Fig. 9 is a section on the line 9—9 of Fig. 8.

Fig. 10 is a plan view, partly in section, of the electrical conductor connections between the brushes and the transformers.

Fig. 11 is a wiring diagram.

Fig. 12 is a wiring diagram of only one of the limit switch and relay hook ups.

Fig. 1 is a front elevation which shows the machine ready for use on the roof of a Pullman car. The car roof is designated R. The track on which the machine travels will be substantially the same curvature as the roof, as is indicated at the bottom of Fig. 1. The electrode units are designated by E in Fig. 1, the third rail or bus bar brush unit by B.

Repeat spot welders are not now broadly new. They may be controlled electrically with an E C & M timer (referred to below) or they may be controlled pneumatically by the reversing valve arrangement shown in the Biederman application, Serial No. 58,916. We desire it to be understood that in carrying out the broad features of

our traveling spot welder, either an electrical control can be used, or a pneumatic control, or, for that matter, a mechanical control may be used, such as a rotating cam shaft, which is old in the prior art.

The point is that after the machine has been started once, the timer is set into operation which controls the "on" cycle, the "off" cycle and the one cycle follows the other until the operation of the machine is stopped as by limit switches.

This machine is designed with what we call "lagging" electrodes, that is to say the electrodes can temporarily remain stationary with the work and then fly back to vertical position after the weld is made notwithstanding the machine is traveling all the time. This machine is arranged to travel and work in both directions by reason of the reversible stops controlled by the control designated S (Fig. 1).

Now coming to the detail and referring to Figs.

1 and 4: 1 designates a lever which operates the reversible two-faced stop S (Fig. 4) which is in the form of a segment carried on shaft 3 which is turned by moving lever 1. In the position shown in Fig. 4, the stop is arranged to engage with the spring-pressed under-cushion 4 which reciprocates in a cylinder carried on lower bracket 5 attached to the electrode cylinder 6. The upper cushion 7 is carried on bracket 8 which is attached to an extension 9 of electrode cylinder 6. This extension 9 pivots the electrode cylinder on the journal 10.

With the machine traveling to the left in Fig. 4, the electrode 11 moves from the position shown in the full lines to the position shown at the right in the dotted lines. With the machine moving to the right, the electrode moves from the position shown in the full lines to the position shown in the dotted lines at the left. In each of these movements, as soon as the air behind the electrode piston 13 is released, the air pressure in the return cylinder 14 operates on piston 15 and snaps the electrodes back to the central full line position shown in Fig. 4. With the stop in the position shown in Fig. 4 where it is arranged to

stop the electrode in its return to neutral position from the left hand dotted line position, the air will be on the underside of the piston 15. As the machine travels to the right in Fig. 4, the electrode lagging behind to the left, the piston 15 is pulled down against the resistance of the air pressure. As soon as the repeat control releases the electrode piston 13, the air pressure on the underside of piston 15 snaps the electrode back to central position. The impact with the stop 2 is cushioned by the cushion 4. Exactly the same operation takes place when the lever 1 is shifted to the right hand position and the cushion 7 at the top cooperates with the face 12 of the stop. But here the air has been turned into

the top of the return cylinder 14. This adjustment of the air from the top to the bottom of the piston 15 is automatically made every time the manual control lever 1 is reversed to start the carriage in its reverse direction. Referring to Fig. 11, it will be seen that when the limit switch 74 is tripped, it deenergizes the solenoid 16 and the valve 18 which controls the air line to the return cylinder 14 and also the air line to the brush control is returned to neutral position.

When the reversing switch 54 is thrown to close the contacts b, this turns the current through the solenoid 17 and this reverses the air in the cylinders 14 and 19.

This conveniently brings up next for discus-

5 10 15 20 25 30 35 40 45 50 55

sion the unit B (see Fig. 1) which is the bus bar brush unit. It will be noted from Fig. 1 that the brushes at the top are adapted for left hand travel and the brushes at the bottom are adapted 5 for right hand travel. Hence, when the machine is traveling to the left, the air is turned into the top of the cylinder 19 and this brings the upper brushes down into contact with the bus bar. The movement of the platform 20 carrying the 10 brushes is limited by the stop nuts 21 and 22 so that the brushes are only pressed lightly in contact with the bus bar. The bus bar is designated 23. This bus bar has hard copper alloy wear strips 24 at top and bottom so as to take the 15 friction of the copper brushes better than pure copper. The bus bar (see Fig. 9) is a flange of the upright conductor 25 which is bolted to the stationary electrode. The stationary electrode is curved to the curvature of the roof and fits 20 under the work, as shown in Fig. 9.

There are two transformers T on the carriage (Fig. 1), one for each pair of electrodes. The brushes are connected with a terminal of each transformer by the laminated conductors 27. An 25 examination of Fig. 2 will show the secondary circuit. One terminal 28 of the transformer T is connected with a copper conductor bar 29 that runs up along the throat of the machine. The laminated jumper 30 (Fig. 1) is connected to this 30 conductor bar and, in turn, is connected to the electrode piston rod at 31 (Fig. 5) below the insulation 32. The secondary current then passes through the work into the stationary electrode 26, thence back to the bus bar 23 through the upper 35 or lower set of brushes and thence through the conductor 34 to the conductor 27. The connection between the brushes and the conductor bars 27 is detailed in Fig. 10. The brushes are carried on a block 35 (see Fig. 3) which is mounted 40 on a slide 34 which slides up and down in a track 110, and is electrically connected to the transformers through the laminated conductor 27 (see Fig. 10).

As long as roll 38 is over the work, air pressure 45 is automatically maintained in the top of cylinder 36 (Fig. 4), pushing down piston 37 which forces pressure roll 38 in contact with the work and holds the work strips together. The course of the air can be seen by consulting the wiring and 50 air diagram (Fig. 11) where it will be seen that the cylinder 36 is connected with the valve 39 which is operated by the solenoid 40.

The carriage is operated by an electric motor M (Fig. 3) which drives reduction gearing 41 55 through a variable speed pulley device. This gearing has a pair of sprocket gears 42 and 43. These, through the chains 44 (Fig. 1), drive the sprocket wheels 45 and 46 which, in turn, drive the shafts 47 which have sprocket wheels 48 and 49 on their 60 ends. These sprocket wheels travel over the stationary chain 50 so as to cause the machine to travel on the track 51 (Fig. 2) on the flanged wheels 53.

The two electrical repeat weld timers indicated 65 in Fig. 11 provide automatic repeat welding control of the particular machine we are describing. Timers of this type are not new and are available on the market. The timer, used on our machine as built, is a product of the Electric Con- 70 troller & Mfg. Co. of Cleveland, Ohio. In general, this timer controls the successive "ons" and "offs" of the repeat welding cycle through a solenoid-actuated air valve which cuts air pressure alternately into the welding and return sides of 75 the electrode cylinder, in response to electrical

impulses from the timer to the solenoid coil of the air valve. Control of the duration of these electrical impulses is effected in the timer by means of rheostats which can be adjusted to vary the time necessary to charge and discharge condensers. This is a general statement of the mode of operation of this type of timer. However, there are a number of different kinds of electrical repeat weld timers, one of which is described in the Wright Patent No. 2,105,899, that it seems unnecessary to go into the detail of these electrical repeat weld timers as they are complicated and the particular kind of timer used has nothing to do with our invention. Furthermore, as first above stated, it would be permissible to use some other form of timer and repeat weld control, such as a mechanical one or a pneumatic one, such as shown and described in the Biederman application, Serial No. 58,916.

The mode of operation of our machine may be 20 described as follows (see Fig. 11):

Say that the carriage is on the right hand end of the track. The lever 1 is thrown to change the position of the stop S (Fig. 4) and, at the same time, operates the reversing switch 54 (as 25 shown in Fig. 7). The actuating mechanism for reversing switch 54 is so designed that link 55 is not moved until shaft 3 approaches the end of its rotary motion, in order to permit lever 1 to be turned freely, with no resisting air pressure 30 against the stops. This is accomplished by the lost motion between the pin 300 and the adjustable set screws or stops 304, 305. Link 55 operates reversing switch 54, closing its contact a and disconnecting b (Fig. 12). Thereby, coil 16 of 35 air valve 18 is energized building up air pressure in the upper part of cylinder 19 which brings the upper set of brushes in contact with the bus bar 23 and supplies air to the return cylinders 14. Through the same contact a of reversing switch 40 54, the reversing motor starter 67 is energized through normally closed limit switch 14 on the other end of track. The contacts of motor starter 67 connect the motor M to the line and release the brake 100. Now the carriage moves toward 45 the left. Trip 65a will close the normally open contact of limit switch 73a momentarily which completes the coil circuit of relay 73, that is, starting from line LB through closed contact of reversing switch 54 through limit switch 14, through normally closed contact of limit switch 71a, through momentarily closed contact of limit switch 73a through coil of relay 73 through fourth finger of reversing motor starter 67 to line Lc. Relay 73 is closed now and is held closed, after 55 limit switch 73a returns to its normal position, through one of its two contacts which is in parallel with the normally open contact of limit switch 73a. The second contact of relay 73 completes the pilot circuit of the timer 101a which 60 controls the operation of welding cylinder 6a.

While the carriage moves continuously to the left, the trip 65a will close limit switch 69a and afterwards 72a. The function of those limit switches is similar to the one 73a already described but operating their corresponding relays 69 and 72. Relay 69 closes the circuit of solenoid 40 of air valve 39 which, in turn, allows air pressure to build up in the upper part of cylinder 36 whereby roller 38 is moved downward holding 70 welding stock on the stationary electrode. Relay 72 completes pilot circuit of timer 101 which controls the operation of welding cylinder 6.

The function of the repeat weld timer, when set in motion by the closing of the pilot circuit, is 75

to furnish electrical energy to the solenoids 59 which will operate the air valves 60 and turn air into the top of the cylinders 6 and 6a and then, when the solenoid is deenergized, reverse the valve 5 which turns air into the lower portion of the cylinders. At the same time, the current is turned into solenoid-controlled primary circuit switches 66 and 76 and these switches are closed, thereby establishing the primary circuit which is, of course, properly timed with respect to the air impulses so that the primary switch is closed after the electrodes engage the work and opened before the electrodes leave the work.

This cycle of operation repeats itself while the carriage moves at practically constant speed. As the carriage approaches toward the left hand side of the track, its trip 65 strikes the limit switch 71a. This momentarily breaks the current flowing to the relay 13. The relay hold-in circuit is broken and the relay flies open, breaking the pilot circuit of timer 101a. Thereafter, trip 65 will strike successively limit switches 68a and 70a whereby the corresponding relay coils 69 and 72 are deenergized. Finally, the trip 65 hits limit switch 74 breaking the motor starter circuit, disconnecting motor M and applying brake 100 and also breaking the current through the solenoid 16 which controls valve 18. The solenoid 16 is deenergized and the air valve 18 returns to neutral position releasing the air in the brush platform actuating cylinder 19 and also in the return cylinders 14.

A new welding operation is started by throwing lever 1 to the opposite side. This changes the position of the stops and, at the same time, operates reversing switch 54. Contact a of reversing switch 54 is then open and contact b closed. Through this contact, coil 17 of air valve 18 is energized, whereby air is supplied to the lower part of cylinder 19, which brings the lower set of contact brushes in contact with the contact bar, and also to the return cylinders 14 to the lower part of the cylinder for the right hand electrode and to the upper part of the cylinder for the left hand electrode. The same contact completes the circuit for the coil of the reversing motor starter releasing brake 100 and starting the motor which propels carriage toward the right. Moving to the right, the trip 65 on the carriage momentarily closes the limit switches 70a and 68a and 71a successively, energizing their corresponding relays 70, 68 and 71 in a similar way as limit switches 73a, 69a and 72a energized their corresponding relays 13, 69 and 72.

Relays 70, 68 and 71 have now the same function as relays 73, 69 and 72 had when the carriage moved toward the left. The function of the timers and air cylinders are the same as described before and, as the carriage approaches toward the right hand side, limit switch 72a releases relay 70, limit switch 68a releases relay 68, limit switch 73a releases relay 71 and limit switch 75 deenergizes the reversing motor starter 67, whereby the motor is disconnected and the brake is applied; and also deenergizes solenoid 17 of air valve 18 which returns to neutral position releasing the air in the brush platform actuating cylinder 19 as well as in the return cylinders 14.

It seems here appropriate to describe more in detail how these limit switches are tripped and re-tripped and how the relays operate. Fig. 11 is a complicated wiring diagram so that, in order to explain the operation, we have selected just one set of relays and two pairs of limit switches. This simplified diagram is Fig. 12. We have taken

the limit switches 68a and 69a which control the relays 68 and 69 which, in turn, control the solenoid 40 that controls the air valve 39 which, in turn controls the pressure roll 38 (Fig. 4). The circuit is traced from line LB, passes through the reversing switch 54, through the motor limit switch 74, through the switch 68a, then to the relay switch 69 but here the circuit is broken. Now, assume that the carriage from its extreme right hand position starts to the left, trip 65a encounters the limit switch 69a and this shorts the current around the broken relay switch 69 and through the solenoid 69b of this switch to the second line Lc. This closes the switch. The left hand switch bar of the relay 69 then closes the circuit from the Lc supply line through solenoid 40 and back to the LB supply line, while current also flows from LB line through the reversing switch 54 through switch 74, limit switch 68a, through the right hand bar of relay 69 and around through the solenoid of relay 69, back to the second line Lc. This forms a holding circuit and, consequently, the relay 69 is held closed even after trip 65a releases the right hand limit switch 69a. Solenoid 40, therefore, is energized during the entire travel of the carriage to the left and the pressure roll is held against the work. In the same way the other pairs of limit switches and relays (Fig. 11) keep the control circuits of the timers closed. Now the left hand trip 65 approaches the limit switch 68a (Fig. 12). It depresses the switch momentarily. This breaks the current to solenoid of relay 69 and that switch flies open. This breaks the current through solenoid 40, reverses valve 39 which reverses the air into the bottom of the cylinder 36 (Fig. 4) and lifts the pressure roll.

The other limit switches operate in the same way on the left hand side, breaking the holding circuits of their corresponding relays. The limit switches are returned to closed position but they do not energize the relays. The reversing switch is now thrown to the right hand position. This reverses the motor and the trip 65 starts back to the right and again trips limit switch 68a. The current then flows from the LB line through the reversing switch 54, through limit switch 75 and through the coil of relay 68 through limit switch 68a through normally closed contacts of limit switch 69a to line Lc. This throws the switch bars closed and this same current now is shorted around limit switch 68a through the left hand bar of relay 68 and through the solenoid of relay 68 to hold the switch closed even after limit switch 68a snaps back to its original or upper position. The current flows from LB line through solenoid 40, the right hand bar of the relay 68 and thence back to the Lc line. All the other limit switches are successively tripped as the carriage moves to the right and the control circuits of the two timers are closed and kept closed until the carriage trips the limit switches at the right.

What we claim is:

1. A traveling welder having in combination a traveling carriage for traveling along the work, a stationary electrode on which the work is supported, an electrode for reciprocating into and out of contact with the work and movable with respect to the carriage to permit the carriage to move while the electrode lags behind in working engagement with the work.

2. A traveling welder having in combination a carriage arranged to move along the work, a stationary electrode on which the work is supported

and a pivotally mounted electrode which is supported on the carriage so that the electrode may remain stationary in contact with the work while the carriage moves along the work, means for reciprocating the electrode into and out of contact with the work and means for furnishing current to the electrode at proper times with respect to the reciprocation of the electrode.

3. A traveling welder having in combination a carriage arranged to move along the work, a stationary electrode on which the work is supported and a movably mounted electrode which is supported on the carriage so that the electrode may remain stationary in contact with the work while the carriage moves along the work, means for reciprocating the electrode into and out of contact with the work and means for furnishing current to the electrode at proper times with respect to the reciprocation of the electrode.

4. A traveling welder having in combination a traveling carriage for traveling along the work, a stationary electrode on which the work is supported, an electrode for reciprocating into and out of contact with the work and movable with respect to the carriage to permit the carriage to move while the electrode remains stationary in engagement with the work and an air cylinder and piston connected to the electrode resisting the tendency of the electrode to lag behind the carriage when the electrode grips the work and immediately returning the electrode to its initial position after the electrode is released from the work.

5. A traveling welder having in combination a traveling carriage for traveling along the work, a stationary electrode on which the work is supported, an electrode for reciprocating into and out of contact with the work and movable with respect to the carriage to permit the carriage to move while the electrode remains stationary in engagement with the work and means yieldingly resisting the lag of the electrode behind the carriage when the electrode grips the work and immediately returning the electrode to its initial position after the electrode is released from gripping relation with the work.

6. A traveling welder having in combination a traveling carriage for traveling along the work, a stationary electrode on which the work is supported, an electrode for reciprocating into and out of contact with the work and movable with respect to the carriage to permit the carriage to move while the electrode remains stationary in engagement with the work, means yieldingly resisting the lag of the electrode behind the carriage when the electrode grips the work and immediately returning the electrode to its initial position after the electrode is released from gripping relation with the work, means for cushioning the electrode when it is returned to its initial position comprising a pair of yieldable members, one located to be operated when the carriage moves in one direction and the other to operate when the carriage moves in the opposite direction, and a reversible stop which can be brought to operate with one cushion or the other depending upon the direction of travel of the carriage.

7. A traveling welder having in combination a traveling carriage for traveling along the work, a stationary electrode on which the work is supported, an electrode for reciprocating into and out of contact with the work and movable with respect to the carriage to permit the carriage to move while the electrode remains stationary in

engagement with the work, means yieldingly resisting the lag of the electrode behind the carriage when the electrode grips the work and immediately returning the electrode to its initial position after the electrode is released from gripping relation with the work, means for cushioning the electrode when it is returned to its initial position comprising a pair of yieldable members, one located to be in operation when the carriage moves in one direction and the other to operate when the carriage moves in the opposite direction, a reversible stop which can be brought to operate with one cushion or the other depending upon the direction of travel of the carriage and means for reversing said stop comprising a reversing switch, electrical connections and a motor in the circuit formed by said connections for driving the carriage in either direction depending upon the direction in which the current is sent through the electrical connections by the reversing switch.

8. A traveling welder having in combination a carriage arranged to move along with the work, a stationary electrode on which the work is supported and a pivotally mounted electrode and electrode cylinder having an extension which is supported on the carriage so that the electrode may remain stationary in contact with the work while the carriage moves along the work, means for reciprocating the electrode into and out of contact with the work, means for furnishing current to the electrode at proper times with respect to the reciprocation of the electrode, a cushion supported on the extension of the electrode cylinder beyond the pivot, and a second cushion supported on the electrode cylinder on the opposite side of the pivot and a rotatable stop reversible to bring the stop into operative relation with one or the other of the cushions depending upon the direction of movement of the carriage.

9. In a traveling welder, the combination of a traveling carriage, a stationary electrode on which the work is laid, an electrode movably mounted on the carriage and arranged to lag behind the carriage when it grips the work while the carriage is moving, means adjacent the electrode and movable with the carriage for pressing against the work to hold the work and fluid means for coincidentally forcing the electrodes into contact with the work and also forcing the said pressure means into movable contact with the work.

10. In a traveling welder, the combination of a stationary electrode on which the work rests, a bus bar connected electrically with the stationary electrode, a carriage movable along the stationary electrode and the work and having a reciprocable electrode movably mounted on the carriage to lag behind the carriage when it grips the work, a set of brushes mounted on the carriage for wiping the bus bar as the carriage moves along the work for completing a secondary circuit and electrical connections including a transformer coil between the brushes and the movable electrode.

11. In a traveling welder, the combination of a stationary electrode on which the work rests, a bus bar connected electrically with the stationary electrode, a carriage movable along the stationary electrode and the work and having a reciprocable electrode, a set of brushes mounted on the carriage for wiping the bus bar as the carriage moves along the work for completing a secondary circuit and electrical connections

including a transformer coil between the brushes and the reciprocable electrode, the said brush set being movable into and out of contact with the bus bar.

- 5 12. In a traveling welder, the combination of a
stationary electrode on which the work rests, a
bus bar connected electrically with the stationary
electrode, a carriage movable along the sta-
tionary electrode and the work and having a
10 reciprocable electrode and two sets of brushes
located on opposite sides of the bus bar and ar-
ranged to be alternatively brought into wiping
engagement with the bus bar to complete the
15 secondary circuit, the direction of movement of
the brushes depending upon the proposed direc-
tion of travel of the carriage.

13. In a traveling welder, the combination
with a secondary circuit including a stationary
electrode on which the work rests and a bus bar
20 connected electrically with the stationary elec-
trode, of a carriage movable along the stationary
electrode and the work and having a reciprocable
25 electrode and two sets of brushes located on op-
posite sides of the bus bar and arranged to be
alternatively brought into wiping engagement
with the bus bar to complete the secondary cir-
cuit, depending upon direction of travel of the
30 carriage and a block for supporting the brushes
in sliding and wiping relation with a portion of
the remainder of the secondary circuit.

14. In a traveling welder, the combination of
a stationary electrode on which the work is sup-
ported, a carriage, an electrode movable with re-
spect to the carriage to permit the electrode to
35 lag behind the carriage when the electrode grips
the work, pneumatic pressure means for return-
ing the electrode to its neutral position, welding
circuits including a set of brushes and a third
40 rail into contact with which the brushes are
pressed, pneumatic means for moving the
brushes, a reversible motor for causing the car-
riage to travel, a limit switch which is automati-
cally tripped by the carriage when it reaches
45 the limit of its movement for reversing the
motor and a reversing switch for reversing the
motor and reversing the air into both pneu-
matic means to reverse the movement of the
brushes and also reverse the fluid operating to re-
turn the electrode to neutral position.

50 15. In a traveling welder, the combination of
a stationary electrode on which the work is sup-
ported, a carriage, an electrode movable with re-
spect to the carriage to permit the electrode to
55 lag behind the carriage when the electrode grips
the work, pneumatic pressure means for return-
ing the electrode to its neutral position, welding
circuits including a set of brushes and a third
60 rail into contact with which the brushes are
pressed, pneumatic means for moving the
brushes, a reversible motor for causing the car-
riage to travel, a limit switch which is automati-
cally tripped by the carriage when it reaches
65 the limit of its movement for stopping the motor,
a reversing switch for reversing the motor and
reversing the air into both pneumatic means to
reverse the movement of the brushes and also
lowered with respect to the work, electrical con-
nections, a valve for controlling the fluid to said
third fluid means and a second limit switch which
is automatically tripped by the carriage near the
limit of its movement thereby stopping the
raising and lowering of said electrodes.

16. In a traveling welder, the combination of
a movable carriage, a welding electrode carried
thereon for welding stationary work while the
carriage is moving, means for reciprocating such
welding electrode repeatedly, a timing control for
controlling such repeated reciprocation and limit
switching means operated by the carriage at the
end of its movement for controlling the timing
control.

17. In a traveling welder, a movable carriage,
a welding instrumentality carried thereon, a
control for such instrumentality, limit switching
means located at each end of the travel of the
carriage, a reversing switch for reversing the
movement of the carriage, the said limit switch-
ing means and reversing switch including elec-
trical circuits, relays, etc., and being paired to-
gether so that when the carriage trips the limit
switch at one end of its travel, it discontinues
operation of the control but after the reversing
switch is thrown to reverse the movement of the
carriage some of the relays can be tripped on
the return movement of the carriage to reestab-
lish the control.

18. In a traveling welder, the combination of
a movable carriage, means including a motor
for moving it back and forth over a prescribed
path, a welding instrumentality carried on the
carriage, a control therefor provided with a con-
trol circuit, limit switching means for controlling
such circuit including a limit switch located at
each end of the travel of the carriage and two
relays operated each by a solenoid wired to
afford a self-holding circuit, one relay being
45 paired with each limit switch by suitable circuits,
and a reversing switch for reversing the current
through the motor and the current to the limit
switching mechanism, the said members being
so arranged that when the limit switch at one
end is tripped, a holding circuit is broken and
the relay switch closing the said control circuit
is broken but whereupon again on the return
travel of the carriage with the reversing switch
swung to reversing position, the other relay is
closed with its self-holding circuit to reestablish
the said control circuit.

19. The combination claimed in claim 18 to-
gether with a limit switch for stopping the motor
and the supply.

20. The combination claimed in claim 18 in-
cluding a pneumatically operated commutator
brush and a control therefor controlled by a limit
switch and also by the reversing switch.

ANTON WAESCHLE.
